UNITED STATES PATENT OFFICE.

PERLEY L. ORMISTON, OF DAYS CREEK, OREGON.

GATE-OPENER.

979,689.

Specification of Letters Patent. Patented Dec. 27, 1910.

Application filed May 13, 1910. Serial No. 561,091.

To all whom it may concern:

Be it known that I, PERLEY L. ORMISTON, citizen of the United States, residing at Days Creek, in the county of Douglas and 5 State of Oregon, have invented certain new and useful Improvements in Gate-Openers; and I do hereby declare the following to be a full, clear, and exact description of the invention, such as will enable others skilled 10 in the art to which it appertains to make and use the same, reference being had to the accompanying drawings, and to the letters and figures of reference marked thereon, which form a part of this specification.

15 This invention relates to new and useful improvements in gate opening devices and comprises various details of construction and combinations and arrangements of parts which will be hereinafter fully described 20 and then specifically defined in the appended claim.

I illustrate my invention in the accompanying drawings, in which:—

Figure 1 is a perspective view of my invention. Fig. 2 is an enlarged detail perspective view showing the manner of swinging the gate. Fig. 3 is a detail perspective view of a convexed plate and showing chain connections therewith. Fig. 4 is a top plan 30 view of the detail shown in Fig. 3, and Fig. 5 is a detail perspective of hinges of the gate.

Reference now being had to the details of the drawings by letter, A designates a post and B is a gate having a gate post B' which, 35 at its lower end, has a hinge member B² engaging a pivotal pin upon the hinge member C which is fastened to the post A. The upper hinge of the gate consists of the member D having an elongated slot D' therein, 40 and D² designates a hinge member which is fastened to the post A and has an integral pin D³ for engagement with the slot D'.

A bar E is bent upon itself at two locations, designated respectively by letters E' and E², which bent portions are positioned 45 parallel to each other and at right angles to the face of the post to which said bar is fastened and said portions E' and E² are apertured for the reception of a rod F, the upper end of which has a crank arm G fixed thereto. A convexed plate H, a detail of 50 which is shown in Fig. 3 of the drawings, is provided with a central opening H' for the reception of the end of the crank G and chains K are fastened to the eyes L project-

ing from said convexed plate, one near the upper and the other near the lower marginal edge thereof. Said chains are connected to the rods J which in turn are pivotally fastened to the opening bars N, which at their inner ends are pivotally mounted 60 on the pivot O which projects from the bar E at a location slightly below the lower of the portions E² of said bar. Ropes or cords Q are fastened to the outer ends of the bars 65 N and afford convenient means whereby an operator may cause the same to swing in one direction or the other.

Fastened to the lower end of the rod F is a crank arm R held to said rod by means of 70 the nut R' and a rod T having an eye T' at one end is connected to an eye T² upon the crank arm R and the other end of said rod T is fastened to an eye bolt S fastened to the front swinging end of the gate. Said 75 eye bolt S has a nut S' mounted upon the threaded end thereof and affords means whereby, as the nut is tightened, the slack may be taken up.

The operation of my invention will be 80 readily understood and is as follows:—The parts being adjusted as shown in Fig. 1 of the drawings, when it is desired to cause the gate to swing in one direction or the other it may be done by the operator pulling upon 85 one or another of the cords Q to cause the bars N to tilt. By reason of the connections J between said bars and the convexed plate, the latter may be caused to tilt in one direction or the other as the chain fulcrums over 90 the convexed surface of the plate. As the plate H tilts, the crank G will be tilted therewith by reason of the free end of said crank arm projecting through the aperture H' and bearing against the edge thereof as 95 the plate is turned. The crank arm G being fastened to the rod F will cause the crank arm R to turn therewith and which will, through the connections of the rod T with the gate, cause the latter to swing in one 100 direction or the other.

What I claim to be new is:—

A gate opener comprising, in combination with a gate post having a flattened top, a bar having two laterally projecting portions 105 thereof bent upon itself and parallel to each other and apertured, one of said portions thus bent extending over and resting upon the flattened top of the post, an angled rod journaled in said apertures of the bar, a 110

collar resting upon a portion of the bar which engages the flat top of the post and supporting said angled rod, a convexed plate fixed to the end of said angled rod, a link fixed to said rod and adapted to actuate a latch, and lever operated connections with said convexed plate.

In testimony whereof I hereunto affix my signature in the presence of two witnesses.

PERLEY L. ORMISTON.
